UNITED STATES PATENT OFFICE.

THOMAS J. KOHUTH AND JOSEPH J. PLOUCH, OF GIPSY, PENNSYLVANIA.

RAIL CLAMP.

Application filed July 23, 1924. Serial No. 727,751.

To all whom it may concern:

Be it known that we, THOMAS J. KOHUTH and JOSEPH J. PLOUCH, citizens of the United States of America, and residents of 5 Gipsy, Pennsylvania, have invented new and useful Improvements in Rail Clamps, which invention is fully set forth in the following specification.

This invention relates to rail fastening devices, and more particularly to such devices employed in connection with metallic railway ties. Such ties are commonly employed in a variety of places where light rails are used such, for example, on tram 15 railways in mines. In such railways, rails of different weights and dimensions are employed such, for example, as twelve and sixteen pound rails, and it is frequently desirable to shift from one weight of rail to 20 another. The present invention is designed to afford an efficient means for clamping the rail to the metallic tie and for quickly releasing the same when desired and substituting a rail of different weight, the whole 25 being performed by unskilled labor and with a minimum consumption of time.

One form which the invention may assume is illustrated in the accompanying drawings, in which—

30 Fig. 1 is a plan view of the invention, showing rails clamped to the tie;

Fig. 2 is a longitudinal section on the line 2—2 of Fig. 1; and

35 Fig. 3 is a transverse section on the line 3—3 of Fig. 1.

In said drawings, 1 indicates a metallic railway tie of any ordinary or suitable construction and, as here shown, consists of a bar of wrought-iron with downwardly 40 turned flanges 2, 2. Extending transversely across said tie is a bar 3 of wrought-iron, one edge portion 4 of which is fixedly secured to the tie by rivets or bolts 5, 5, the other edge portion 6 of said transverse bar 3 45 being bent or inclined upwardly sufficiently to permit the flange 7 of the rail 8 to pass thereunder and, when forced well over as shown in Fig. 2, is firmly engaged by the under surface of the part 6 of said transverse bar. On the opposite side of the rail from the bar 3 is a second bar 9, preferably corresponding in every particular to the bar 3, and bolts 10, 10 extend through the outer edge portion 11 of said bar and 50 through two longitudinally extending parallel slots 12, 12 formed in the tie 1, a washer

13 (Fig. 2) being preferably interposed between the nut on the bolt and the under face of the tie. The nuts 14 on these bolts 10, 10 are tightened sufficiently to cause the bar 9 60 to snugly fit against the upper surface of the tie 1, but loose enough to permit the same to be adjusted longitudinally along the slots 12, 12. The inner edge portion 15 of the bar 9, that is the portion adjacent the rail, 65 is bent so as to incline slightly upward corresponding to the upwardly inclined portion of the bar 3.

Pivoted to the tie 1 and adjacent to the bar 9 is a third bar 16 turning freely on 70 the pivot 17 which may be a rivet or bolt if desired, here shown as a rivet. The ends of this bar 16 are cam-shaped, the cam on the end 16' being nearer the pivot than the cam on the end 16'', and the location of the 75 pivot 17 being such that, when either of the cam ends 16' or 16'' is turned around in the direction of the slideable bar 9, they engage the outer edge portion 11 thereof and force the said bar 9 toward the flange 7' of the rail 8. The lengths of the longitudinally extending slots 12, 12 are such as to enable the bar 9, when the cam bar 16 is turned transversely of the rail 1, to be drawn a 80 sufficient distance from the clamping bar 3 85 to admit the flange of the heaviest rail designed to be employed. The rail being inserted with the flange 7 under the upwardly inclined edge portion 6 of the transverse bar 3, the transverse clamping bar 9 is 90 shoved toward the rail, the bolts traveling in the slots 12, 12, and the cam bar 9 is turned so that one of its cam-shaped ends engages the outer edge portion of the slideable transverse bar 9 and forces it toward 95 the rail until the under surface of the upwardly inclined portion 15 of said slideable bar snugly engages the flange 7' of the rail. If it is desired to substitute a rail of different weight, it is only necessary to turn the 100 cam bar 16 on its pivot, slide the transverse bar 9 away from the rail when the latter can be readily lifted out and another rail substituted. The lengths of the slots 12 not only permit the transverse bar 9 to slide far 105 enough away to permit the insertion of the broadest flanged rail to be employed, but also permit the said transverse slideable bar 9 to be slid toward the rail a sufficient distance to snugly engage the smaller size of 110 rail designed to be employed.

In order to insure the cam end of the

cam member 16 remaining in tight engagement with the slideable transverse bar 9, suitable locking means may, if desired, be employed. Such locking means is here shown in the form of a pin 18 extending through a hole 19 in the cam bar 16 and into a hole 20 in the tie 1. While such locking pin may, in some cases, be desirable, it may of course be omitted.

10 It will be observed that the entire structure is one that may be cheaply manufactured and assembled, and when assembled may be quickly and efficiently operated. The transversely extending clamp bars 3 and 9 can be made by simply cutting off a piece of wrought-iron bar and bending up the edge portion thereof and drilling holes therethrough, and the cam bar 16 may be cheaply and quickly made out of an ordinary wrought-iron plate. The whole device is such that one rail may be taken out and another substituted in a few minutes and by unskilled labor, and yet guarantees that the rails be firmly clamped to the tie without regard to whether the rails employed be of the larger or smaller size.

What is claimed is:—

1. The combination of a metallic railway tie, and a rail jaw fixedly secured thereto, with an adjustable rail jaw slidably secured to said tie opposite said fixed jaw and a plurality of cams pivoted to said tie in position to engage said slideable jaw at different

distances from said fixed jaw, whereby rails of differing dimensions may be readily secured to said tie. 35

2. The combination of a metallic railway tie and a rail jaw fixedly secured thereto, with a slideable jaw secured to said tie opposite said fixed jaw, and a bar pivoted to 40 said tie and having cam-shaped ends at unequal distances from the pivot thereof, whereby said slideable jaw may be adjusted into clamping engagement with rails of different sizes. 45

3. The combination of a metallic railway tie, a bar of metal extending across said tie and having one edge portion fixedly bolted to the tie and its other edge portion inclined upward from the tie, whereby said bar forms a fixed rail jaw, a second bar extending across said tie opposite said first bar and having bolts extending through one edge portion thereof and through longitudinally extending parallel slots in said tie while its 50 opposite edge portion is inclined upward from the tie, and a bar of metal having cam-shaped ends pivoted to said tie in position for said ends to engage said second transverse bar and with its pivot nearer to one 55 end of the bar than to the other.

In testimony whereof we have signed this specification.

THOMAS J. KOHUTH.
JOSEPH J. PLOUCH.
